UNITED STATES PATENT OFFICE.

JOHN STEINOCHER, OF WEST, TEXAS.

AUTOMATIC GUN FIRING MECHANISM.

1,056,602.

Specification of Letters Patent.

Patented Mar. 18, 1913.

Application filed October 15, 1912. Serial No. 725,888.

To all whom it may concern:

Be it known that I, JOHN STEINOCHER, a citizen of the United States, residing at West, in the county of McLennan and State of Texas, have invented new and useful Improvements in Automatic Gun Firing Mechanism, of which the following is a specification.

The primary object of this invention is the provision of protective means for gardens, orchards and fields for scaring off birds, animals and such like as tend to prey upon or devastate crops, stock or like property.

The invention embodies a fire arm of the magazine type and has relation to novel mechanism for discharging the fire arm at predetermined intervals, such mechanism operating the fire arm in a manner to eject the empty shell and to place a cartridge in firing position and to operate the trigger for exploding such cartridge, the mechanism including a train of gearing and a primary actuator such as a windmill or other source of power.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a side view of an automatic gun firing mechanism constructed in accordance with and embodying the essential features of the invention. Fig. 2 is a detail view of the means for operating the loading and firing mechanism of the gun, showing such parts on a larger scale. Fig. 3 is a detail view of the connecting means between the barrel of the fire arm and the tower of the windmill. Fig. 4 is a detail view of the means for operating the trigger of the gun. Fig. 5 is a detail view showing more clearly the parts associated with the slide or grip by means of which the fire arm is charged after each explosion or fire.

Corresponding and like parts are referred to in the following description, and indicated in all the views of the drawings, by the same reference characters.

The numeral 1 designates a small gun or fire arm of the magazine type. This gun is secured by suitable means in a given position and is automatically fired at predeter-

mined intervals, the operation being entirely automatic, the noise incident to the discharge being designed to frighten off beasts, birds and animals of prey, thereby protecting the garden, orchard or field in which the mechanism is located.

A motor or primary actuator is essential for operating a train of gearing by means of which the gun is fired. For convenience the primary actuator or motive power is illustrated as consisting of a windmill 2. A train of gearing 3 is arranged to be operated by means of the windmill and embodies a worm gear 4, which is in mesh with a worm 5 forming a part of a shaft geared to the shaft of the windmill so as to be operated thereby. The train of gearing also embodies a tappet wheel 7, which is provided with two tappets 8 and 9 so positioned as to operate the loading and firing mechanisms. The train of gearing is mounted upon a framework 10, which is connected with the tower of the windmill to form in effect a part thereof.

The gun 1 is placed upon a platform 11, which forms a part of the framework 10 and is stepped into a block 12 secured to the platform. The bars 13 have their outer ends clamped to the barrel of the gun near the muzzle and are secured at their rear ends to uprights of the windmill tower. The bars 13 are forwardly converged, thereby bracing the gun laterally. A rod 14 is connected at its upper end to the outer ends of the bars 13 and a helical spring 15 of the contractile type connects the lower end of the rod 14 with the slide or grip 16 of the gun. When the slide or grip 16 is moved the ejector and loading mechanism are operated to discharge the empty shell and to place a cartridge in position to be discharged at the next operation of the firing mechanism. The slide is moved downward against the tension of the spring 15 by the operating mechanism and is returned to normal position by means of the said spring 15.

A lever 17 is pivoted between its ends to an upright or bracket 18 secured to the framework 10 and has a fork 19 at its outer end which embraces opposite sides of the forestock of the gun and has its fork members connected by means of links 20 with the slide or grip 16. The rear end of the lever 17 extends within the path of the tappet 8 to be operated thereby for moving the slide 16 downward when recharging or

loading the gun. A lever 21 is fulcrumed to the upright or bracket 18 at a point between its ends. The rear end of the lever 21 extends across the path of the tappet 9 to be operated thereby for firing the gun. A link 22 is pivotally connected at its upper end with the outer end of the lever 21 and its lower end is bent, as indicated at 23, to extend across the path of the trigger 24 to detect 5 press the same and fire the gun. A spring 25 coöperates with the lever 21 to return it to normal position after the gun has been discharged.

It is to be understood that the train of 15 gearing may be of such arrangement and the tappet wheel of such diameter as to insure a firing of the gun at stated intervals. After the magazine of the gun has been charged and the parts arranged for firing the gun 20 the latter will be automatically discharged by the operation of the primary actuator through the train of gearing and tappet mechanism, the slide or grip 16 being operated to eject the empty shell and to place a 25 cartridge in firing position, after which the trigger 24 is operated to explode the cartridge and fire the gun, the noise of which will frighten off birds, beasts and animals of prey.

30 From the foregoing description, taken in connection with the accompanying drawings, the advantages of the construction and of the method of operation will be readily apparent to those skilled in the art 35 to which the invention appertains, and while I have described the principle of operation of the invention, together with the device which I now consider to be the best embodiment thereof, I desire to have it 40 understood that the device shown is merely illustrative, and that such changes may be

made when desired as are within the scope of the claims appended hereto.

Having thus described the invention what is claimed as new, is:—

45

1. In means for automatically discharging a magazine gun, the combination of an actuating mechanism, a tappet mechanism for moving the slide or grip of the gun in one direction, means for automatically returning said slide to normal position, a tappet mechanism for operating the trigger of the gun, and means for automatically resetting the tappet mechanism.

50

2. In automatic means for discharging a magazine gun, the combination of a tappet wheel having two tappets, a lever connected with the slide of the gun and arranged to be operated by one of the said tappets, a second lever arranged to be operated by the other one of the tappets, and connecting means between said second lever and the trigger of the gun for firing the latter.

55

3. Means for automatically firing a gun, the same comprising a gun support, bars having connection with the barrel of the gun for holding the latter in a given position, a tappet wheel having two tappets differentially positioned, actuating means for the tappet wheel, a lever arranged to be operated by one of the said tappets and having connection with the slide of the gun, and a second lever adapted to be actuated by the other one of said tappets and arranged to trip the trigger of the gun.

60

70 In testimony whereof I affix my signature in presence of two witnesses.

JOHN STEINOCHER.
